CONTROLLED LOCK CO., OF SAN FRANCISCO, CALIFORNIA, A CORPORATION OF
CALIFORNIA.

COIN-CONTROLLED LOCK.

1,076,822.

Specification of Letters Patent.

Patented Oct. 28, 1913.

Application filed June 20, 1912. Serial No. 704,745.

To all whom it may concern:

Be it known that I, WILLIS S. FARNSWORTH, a citizen of the United States, residing in the city and county of San Francisco and State of California, have invented new and useful Improvements in Coin-Controlled Locks, of which the following is a specification.

This invention relates to coin-controlled locks, and particularly pertains to a lock in which the operation of the key therefor is controlled by a coin.

It is the object of this invention to provide a coin-controlled lock, by means of which the latch bolt of the lock will be prevented from being operated until the deposit of a proper token, and which is so constructed as to admit of the key being withdrawn or thrown only on the deposit of a proper coin or token.

Another object is to provide an attachment of the above character which is adapted to be mounted on the face or escutcheon plate of the lock without necessitating any alterations of the lock mechanism.

Another object is to prevent the clogging of the coin pocket by the deposit of a coin while another coin is already in the pocket.

A further object is to construct a coin-controlled attachment which will occupy a minimum amount of space, which will have a minimum number of parts and in which the coin-advancing means or the means by which the coin is made effective to release the lock is mechanically and positively actuated, in contradistinction to the ordinary coin-controlled mechanism or locks wherein the coin acts simply by gravity.

The invention resides in a rockable member mounted to be operated by a key in the lock, and means for normally locking the rockable member against movement to hold the key in an angular position in relation to the keyhole of the lock, said means being operable on the deposit of a coin to permit the key being turned to throw the lock bolt and thereafter be withdrawn.

The invention consists of the parts and the construction and combination of parts as will be hereinafter more fully described and claimed, having reference to the accompanying drawings, in which—

Figure 1 is a front view of a lock with the attachment applied, showing the bolt

thrown and the key withdrawn. Fig. 2 is a side elevation of same. Fig. 3 is a rear elevation. Fig. 4 is a detail of the mechanism controlled by a coin, showing it in its normal position with a coin in place as just deposited. Fig. 5 is a similar view showing the parts in their operated positions. Fig. 6 is a detail section on the line V—V of Fig. 4. Fig. 7 is a section on the line W—W of Fig. 5. Fig. 8 is a section on the line X—X of Fig. 4. Fig. 9 is a section on the line Y—Y of Fig. 5. Fig. 10 is a section on line Z—Z of Fig. 1, partly in elevation.

In the drawings, A represents the face plate or escutcheon of an ordinary lock, here shown as a lock of the "Yale" type, in which the bolt B is operated by a bit C on a revoluble barrel D, the rotation of which is effected by means of a key E in the usual well-known manner. It will be apparent, however, that the invention is applicable for use on other types of locks than that here shown; the one essential feature required in the lock being that the key be unremovable from the lock when positioned at an angle in relation to the keyhole. An important feature of this invention resides in providing a means for normally retaining the key in this angular position in the lock with the bolt in its retracted position, which means can be released to permit the operation of the lock only on the deposit of a certain coin.

In carrying out my present invention, a plate 2 is rigidly mounted on the barrel D upon the outer face of the escutcheon A; the plate 2 being provided with a keyhole 3 registering with the keyhole E. This plate 2 is designed to be rocked when the key E is operated. Pivotedly connected to the back of the plate 2 on opposite sides of the barrel D are downwardly depending arms 4 and 5; the upper ends of these arms being connected to the plate 2 by means of screws 6 which pass through curved slots 7, formed in the escutcheon A. The slots 7 act in conjunction with the screw 6 to limit the rocking movement of the plate 2. The arms 4 and 5 extend downwardly adjacent to the rear side of the escutcheon A. The arm 5 is guided at its lower end between outwardly extending pins 8 and 8' mounted on the back of the escutcheon A; the arm 5 having a

plate 9 mounted on its lower end. This plate has a vertical edge paralleling the outer edge of the arm 5 which abuts against the pin 8. The pins 8-8' thus securely hold 5 the lower end of the arm 5 against side- 70 wise movement, but permit of its being oscillated by the rotation of the plate 2, as will be later described. The inner edge of the lower end of the arm 4 is designed to contact 10 the pin 8 and is held thereagainst by means of a plate spring 10, mounted on a bracket 11 carried on the escutcheon plate A, which spring bears against a pin 12 mounted on the arm 4. The pin 8 thus 15 serves to limit the inward movement of the arm 4 and also limits its downward movement, when actuated by the plate 2, by reason of its engagement with a shoulder 13 formed on the arm 4. It will be observed 20 that the arm 4 may be rocked outwardly away from the pin 8 in opposition to the plate spring 10.

Mounted on the lower end of the arm 4 is an inwardly extending plate 14, which 25 projects over the lower end of the arm 5 and forms a coin slot between the lower ends of the arms 4 and 5, into which the coin may be inserted through a slot 15 formed in the escutcheon A. A coin deposited in 30 the slot 15 is designed to come to rest upon a shoulder or abutment 16 formed on the inner edge of the arm 5 where it is supported by reason of its opposite edge bearing against the inner edge of the arm 4; 35 the coin indicated at G resting on the shoulder 16 below an inwardly extending coin-pusher 17 carried by the arm 4.

When the key E is in the lock and the bolt B is in its retracted position, the lower 40 ends of the arms 4 and 5 will be positioned, as shown in Fig. 4, in which position the downward movement of the arm 4 is limited by means of the pin 8 and the shoulder 13 so as to prevent the plate 2 being rocked 45 by the key E sufficiently far to allow the latter to be disposed in its vertical position in relation to the keyhole 3. By this construction the key E is prevented from being withdrawn from the lock and also blocked 50 against movement, thereby preventing the operation of the bolt B.

In the operation of the invention when it is desired to throw the bolt B and withdraw the key E, a token of a certain diameter or 55 denomination is deposited in the slot 15, where it comes to rest upon the abutment 16 between the lower ends of the arms 4 and 5, as before described and as shown in Fig. 4. The shoulder 13 being spaced a short 60 distance above the pin 8 will admit of a limited downward movement of the arm 4 and a consequent slight rotation of the plate 2. This movement of the plate 2 is effected by turning the key E, after the coin G is 65 deposited, in such a manner as to move the

arm 4 in a downward direction and the arm 5 in an upward direction. The upward movement of the arm 5 carries the coin G therewith so as to bring its upper edge into contact with the lower edge of the coin- 70 pusher 17 on the arm 4. The downward movement of the arm 4 causes the member 17 to engage the coin G and move it downwardly in opposition to the arm 5, causing it to press against the abutment 16 and 75 force the arm 4 outward away from arm 5, as indicated in dotted lines in Fig. 4, so as to cause the shoulder 13 to clear the pin 8. This will admit of a continued rotary movement of the key E and the plate 2, so 80 as to throw the bolt B into locked position and dispose the key E in the vertical position and admit of its being withdrawn from the lock. In thus locking the bolt, arm 5 moves up and arm 4 down. The coin on 85 passing over the abutment 16 falls upon a stop shoulder 18 on the inner edge of the lower end of the arm 5, where it comes to rest with its opposite edge against the inner edge of the arm 4. The coin G in passing 90 over the abutment 16 releases the lower end of the arm 4 so that it moves inwardly by the action of the spring 10 to throw the pin 8 into engagement with a V-shaped notch 95 19 formed on the inner edge of the arm 4. Formed in the escutcheon plate A is a perforation 20 which registers with a similar 100 perforation 21 formed in the plate 9, when the arm 5 is in its uppermost position, so that the coin G, when resting upon the shoulder 18 as shown in Fig. 5, may be observed 105 through the escutcheon plate. The coin G in moving downward passes below the pin 8, as indicated in dotted lines in Fig. 5, where it is released from the shoulder 18 and deposited in any suitable receptacle. The arm 4 in moving upward is moved outwardly by reason of the inclined face of the 110 notch 19 riding over the pin 8, so as to permit the coin G passing between the lower end of the arm 4 and the shoulder 18 on the arm 5. The moment the coin G is released from between the shoulder 18 and the arm 4, the latter is moved back into its 115 normal position by means of the plate spring 10, thereby re-positioning the pin 8 below the shoulder 13 on the arm 4 in such a position as to prevent the operation of the lock until another coin has been deposited.

From the foregoing it is seen that the arms 4-5 in conjunction with the escutcheon plate A and back plate 14 and shoulders 16-18 constitute in effect a sliding pocket for the coin, through which pocket the coin is advanced step by step positively; first, 120 when engaged by the pusher 17; and secondly, by the engaging of the abutment 16 behind the coin, the arm 4 yielding toward and from arm 5 sufficient to accomplish the 125 desired purpose.

Having thus described my invention, what I claim and desire to secure by Letters Patent is—

1. In a coin-controlled lock, the combination of a latch bolt, a barrel for reciprocating the same, a key for turning the barrel, a pair of oppositely movable arms operable by the key, one of said arms having a limited yielding movement toward and from the other arm, and one of said arms also carrying an abutment to support a coin, coin pocket-forming means coöperating with the arms to hold the coin, and means carried by one arm to advance the coin past the abutment formed on the other arm.
2. In a coin-controlled lock, the combination with a latch bolt, of a barrel connected therewith to move the bolt, a key for operating the barrel, coin-controlled mechanism permitting of but a single complete reciprocation of the bolt on the deposit of a single coin, said mechanism including a pivoted plate connected with the barrel for sliding movement, a pocket formed with said plate, an opposed co-acting wedge-shaped abutment, between which and said sliding plate a coin is adapted to be held, and means carried by the sliding plate for advancing the coin past said abutment.
3. In a coin-controlled lock, the combination with a sliding latch bolt, of a key-operated barrel for actuating the bolt, a pair of oppositely sliding arms connected with the barrel and reciprocal thereby, means co-acting with the arms to inclose a coin pocket, said arms having a limited yielding movement toward and from each other, and means coöperating with the arms by which the key is normally held against withdrawal from the barrel.
4. In a coin-controlled lock, the combination with a sliding latch bolt, of a key-operated barrel for actuating the bolt, a pair of oppositely sliding arms connected with the barrel and reciprocal thereby, means co-acting with the arms to inclose a coin pocket, said arms having a limited yielding movement toward and from each other, means co-operating with the arms by which the key is normally held against withdrawal from the barrel, and means in conjunction with the arms whereby, upon deposit of the coin, the bolt may be projected into locked position and the key withdrawn and subsequently the bolt retracted by the key, whereupon the key assumes its normal position against withdrawal until the deposit of another coin.
5. The combination with a latch bolt, of a barrel having a lug to operate the bolt, a key to operate the barrel, and coin-controlled mechanism including a sliding coin pocket connected with the barrel to allow

the latch bolt to be operated only on the deposit of a proper token.

65

6. In a lock, the combination of a turnable key-actuated member, a pair of arms pivoted to the member on opposite sides of the center, a coin pocket formed by said arms, detent means for preventing the rotation of the member until the deposit of a coin in the pocket, and release mechanism controlled by the coin.

70

7. In a coin-controlled lock, the combination of a rockable member controlled by a key, a pair of parallel arms connected with said rockable member, means for limiting the movement of the rockable member, means for supporting a coin between said arms, and means whereby the coin will act to permit an increased movement of the rockable member.

75

8. In a coin-controlled lock, the combination of a pair of parallel arms, a pivoted member to which said arms are attached on opposite sides of the pivotal point, means for limiting the movement of the pivoted member, and means controlled by a coin between said arms for permitting an increased movement of the rockable member.

80

9. In a coin-controlled lock, the combination of a pair of parallel reciprocating members, a rockable plate for reciprocating said members controlled by a key, means for supporting a coin between said members, means for limiting the movement of said members and the rockable plate, and means whereby an initial movement of the rockable plate will co-act with the coin to permit an increased movement of the rockable plate.

85

10. In a coin controlled lock, the combination of a pair of reciprocating members, means for reciprocating said members in opposite directions, a stop for one of said members, and means controlled by a coin for rendering said stop ineffective to limit the movement of said member.

95

11. In a coin controlled lock, a pair of oppositely disposed reciprocating members having a limited movement toward and from each other, a push bar carried by one of said members, a cam face upon the other of said members directed toward said push bar, a coin chute for delivering a coin edge-wise between said push bar and said cam face, and means for reciprocating said members in opposite directions to grip said coin between said push bar and said cam face to separate the said members.
